UNITED STATES PATENT OFFICE.

HENRY H. FORSYTH, OF CHICAGO, ILLINOIS.

COUPLING-CENTERING DEVICE.

SPECIFICATION forming part of Letters Patent No. 727,929, dated May 12, 1903.

Application filed February 26, 1903. Serial No. 145,206. (No model.)

To all whom it may concern:

Be it known that I, HENRY H. FORSYTH, a citizen of the United States, residing at Chicago, in the county of Cook and State of Illinois, have invented certain new and useful improvements in Coupler-Centering Devices, of which the following is a specification.

My invention relates to coupler-centering devices for railway-cars, having reference more particularly to that class of devices now coming into extensive use in railway practice for automatically centering the coupler-heads of draw-bars through the provision of elastic means operating laterally upon the draw-bars to return them to a position substantially coincident with the longitudinal center line of the car.

Draw-bar guides have heretofore been devised and employed in practice wherein the draw-bar guiding or centering element is composed of a single part provided with projections or lugs adapted to engage the opposite sides of the draw-bar and normally tend to return it to central position to whichever side the bar is swung. It has been found in practice that where these guides are positioned close enough to the sides of the draw-bar in the normal central position of the latter to render effective service in centering the same when the latter is swing to one side through a considerable angle the guiding-lugs tend to bind upon the sides of the draw-bar, owing to the fact that the distance between them transversely of the draw-bar is lessened the farther the latter swings to one side, and hence said guiding-lugs are frequently broken off and rendered ineffective for their intended purpose.

My invention has for its primary object to provide a centering device of this general type, but of such a construction as to eliminate the objectionable feature above pointed out, and this object I carry out primarily through the provision of a two-part guiding means, the parts of which serve, respectively, to center the draw-bar in association with a common operating medium for said two-part guide, which in the preferred form of my invention permits a movement of either of the parts of the draw-bar guide independently of the other, but which within the purview of my invention may operate to simultaneously

actuate said parts of the guide in opposite directions.

A device which illustrates the principle of my invention is shown in the accompanying drawings, wherein—

Figure 1 is a top plan view of a preferred form of my invention, the draw-bar broken off being indicated in dotted lines. Fig. 2 is a rear end view of the same, and Fig. 3 is a view similar to Fig. 1 of a modified form of the invention.

Referring to the drawings for a more detailed description of the forms of my invention which I have selected to illustrate the same, 5 designates the transversely-extending carry-iron in the usual form, which is ordinarily suspended from the under side of the end of the car-body. Rigidly secured on said carry-iron is a stationary plate 6, the front margin of which is preferably flush with the forward edge of the carry-iron, while its rear portion is extended for some distance rearwardly of the inner or rear margin of the carry-iron and is somewhat widened and has its edge turned up to form a vertical flange 7. The ends of the flange 7 are inwardly turned or curved, as shown at 7^a, and constitute fulcrums for the elements of a two-part draw-bar guide or saddle, which elements are designated by 8 and 9, respectively. These elements are of identical but inverse construction, being provided at their forward ends with upstanding lugs 8^a and 9^a, respectively, and at their rear ends with rounded projections or knuckles 8^b and 9^b, respectively, designed to fulcrum with a rocking movement against the seats formed at 7^a in the flange 7 of the stationary plate 6.

In the inner or rear ends of the guide-plates 8 and 9 are a pair of pins 10 and 11, respectively, depending from the under sides of said plates and engaging slots 12^a and 12^b, respectively, formed in the outer ends of a connecting-bar 12, underlying the rear ends of said plates, which bar is centrally pivoted, as by a pin 13, to the inner end of a rod or bolt 14, which extends rearwardly through an aperture in the flange 7 and is surrounded by a coiled compression-spring 15. One end of this spring abuts against the outer face of the flange 7, while its opposite end abuts a collar 16, passed over the outer end of the

rod 14 and retained thereon by a nut 17. It will be observed that the inner end of the rod 14, which lies inside the marginal flange 7 of the stationary plate, is provided with a 5 shoulder 14^a, which abuts the inner face of the flange, thus limiting the outward movement of the rod 14 and consequently the inward travel of the members 8 and 9 of the draw-bar guide toward each other. 18 designates the draw-bar broken away at its ends, said bar being shown in dotted lines in Fig. 1 and in transverse section in Fig. 2.

The operation is as follows: When the draw-bar is swung radially, as in passing 15 around a curve, in the direction of the guiding-lug 8^a, so as to engage and force outwardly the latter, the plate 8 is rocked on its fulcrum and its pin 10 is drawn toward the front margin of the plate 6, whereby the bar 12 is 20 oscillated on the pin 11 as a fulcrum, thereby placing the spring 15 under partial compression. During this operation the guide 25 9 remains substantially stationary, whereby the distance between the draw-bar-engaging lugs 8^a and 9^a is constantly increased the farther out the plate 8 swings, thereby providing between said guide-lugs ample clearance 30 to accommodate the maximum angular movement of the draw-bar. Obviously the same relative operation of the parts takes place when the draw-bar swings in the opposite direction and engages the guide-lug 9^a.

Fig. 3 illustrates a modified form of connection between the spring-bolt 14 and the 35 guide-plates 8 and 9. In this form of the invention the rear ends of said guide-plates are connected to the inner end of the spring-bolt through the interposition of links 20 and 21, respectively, which links have pivotal connections with said parts by means of pins 22 and 23 in the plates 8 and 9, respectively, and a pin 24 uniting the meeting ends of said links to the end of the spring-bolt.

By reason of the last-described construction 45 when the draw-bar engages one of the guide-lugs 8^a or 9^a and swings the same outwardly a similar movement is simultaneously imparted to the companion guide-lug, thereby increasing the distance between said guide-lugs 50 as the draw-bar swings outwardly through the simultaneous travel of said lugs in opposite directions away from each other. Such an operation obviously provides a maximum clearance to accommodate the angular swing of 55 the draw-bar, and it is also evident that the centering effect of the spring 15 acts simultaneously and equally upon both guides, so that when the draw-bar is returned to normal 60 position both guide-lugs are likewise in normal position ready to operate in the manner described upon the next outward movement of the draw-bar.

I am aware that a two-part draw-bar guide in the form of presser heads or plates engaging the sides of the draw-bar and backed by independent springs is old in the prior art. A 65 single-part guide-plate having projecting lugs

engaging the respective sides of the draw-bar, adapted to move laterally in both directions and operated by a single elastic medium, is 70 also old; but so far as I am aware I am the first to provide a multipart draw-bar guide or centering device the individual parts of which are actuated by a common operating medium, and this whether said parts be so arranged as 75 to move independently of each other or to move simultaneously. I do not, therefore, limit myself to the interpretation of my invention to the particular embodiment thereof herein illustrated and described nor to the 80 particular forms nor relative arrangement of the elements as set forth, so long as the distinguishing novel principle and characteristic of my invention is preserved, which may be stated generally to reside in the combination, 85 with a support, of a multipart draw-bar guide and an operating medium common to the several parts of said guide.

I claim—

1. In a coupler-centering device, the combination with a stationary support, of a multi-part draw-bar guide carried thereby, and a common actuating means for the individual parts of said guide, substantially as described. 90

2. In a coupler-centering device, the combination with a stationary support, of a two-part draw-bar-centering guide carried thereby, and a common actuating means for both parts of said guide, substantially as described. 95

3. In a coupler-centering device, the combination with a stationary support, of a fulcrumed multipart draw-bar-centering guide carried thereby, and a common operating medium for the individual parts of said guide, 100 substantially as described. 105

4. In a coupler-centering device, the combination with a stationary support, of a fulcrumed two-part draw-bar-centering guide carried thereby, and a common operating medium for both parts of said guide, substantially as described. 110

5. In a coupler-centering device, the combination with a stationary support, of a multi-part draw-bar-centering guide carried thereby, the parts of which are independently movable, and a common operating medium for the individual parts of said guide, substantially as described. 115

6. In a coupler-centering device, the combination with a stationary support, of a two-part draw-bar-centering guide carried thereby, both parts of which are independently movable, and a common operating medium for said parts of the guide, substantially as described. 120

7. In a coupler-centering device, the combination with a stationary support, of a fulcrumed two-part draw-bar-centering guide carried thereby, the parts of which are independently movable, and a common operating medium for said parts of the guide, substantially as described. 125

8. In a coupler-centering device, the combination with a stationary support, of a two-

part draw-bar-centering guide, the parts of which have vertically-extending lugs engaging the sides of the draw-bar respectively, of a single operating medium connected to and actuating both parts of the guide, substantially as described.

9. In a coupler-centering device, the combination with a stationary support, of a two-part draw-bar-centering guide carried thereby, the parts of which are fulcrumed and provided with vertical lugs engaging the sides of the draw-bar, respectively, and a common actuating-spring connected to and operating both parts of said guide, substantially as described.

10. In a coupler-centering device, the combination with a stationary support, of a two-part draw-bar-centering guide, the parts of which are independently fulcrumed and provided with vertical lugs engaging the sides of the draw-bar, respectively, an actuating-spring, and connections between said spring and the parts of the guide permitting a lat-

eral movement of either part independently of the other, substantially as described. 25

11. The combination with a hanger-iron, of a stationary plate secured thereto, a pair of inversely-disposed draw-bar-guiding members fulcrumed thereon, a single actuating-spring, and pivoted connections intermediate 30 said members and said spring permitting independent lateral movements of said members, substantially as described.

12. In a coupler-centering device, the combination with a stationary support, of a fulcrumed two-part draw-bar-centering guide carried thereby, a common actuating means for both parts of said guide, and means limiting the inward movement of said parts of the guide toward each other, substantially as 35 40 described.

HENRY H. FORSYTH.
